UNITED STATES PATENT OFFICE

2,418,593

CRANE WEIGHT AND RADIUS INDICATOR

Walter R. Martin, Lowell Linder, and Harold J. Blythe, Long Beach, Calif., assignors, by mesne assignments, to said Martin

Application October 26, 1943, Serial No. 507,732

6 Claims. (Cl. 265—47)

1

This invention relates to an indicating structure, and particularly pertains to a crane weight and radius indicator, and is a continuation in part of our application for United States Letters Patent Serial No. 445,312 filed June 1, 1942.

In the operation of hoisting apparatus, and particularly cranes of various types, a platform suitably supports a control cab and an adjustable boom. The boom is fitted at its outer end with a main block carrying tackle controlled from the cab. A vertically swinging boom has attached to it boom rigging, whereby the vertical inclination of the boom may be adjusted. In other types of cranes the effective length of the boom may be changed by other than vertical swinging action. It is well known that the maximum weight supporting strength of a boom depends upon the overhanging length of the boom, and in vertically swinging cranes varies with the angle of inclination of the boom to the horizontal. This length is designated by a factor known as the "radius of the boom." On cranes having a vertically swinging boom the radius is measured along a horizontal plane intersecting the heel pin of the boom and extending from the vertical axis of the crane to a line perpendicular to the horizontal plane and intersecting the point of support of the main hoisting block upon the free end of the boom. It will thus be evident that the aforementioned horizontal plane measured from the heel pin to said perpendicular line will represent the base of a triangle, and that the length of the boom will represent the hypotenuse of the triangle, with the remaining side of the triangle represented by the perpendicular line of altitude. The angle between the base and the hypotenuse will vary as the boom swings vertically toward and away from the plane of the base. At the same time the base line will vary in length representing different lengths of radii. Upon the different lengths of radii and the corresponding angle between the base and hypotenuse of the triangle the maximum weight carrying capacity of the boom in any set position is determined. Heretofore it has been necessary for an experienced operator to approximate the set angle of the boom and the radius. In instances where the crane operator's estimate was inaccurate disastrous results occurred due to the fact that when an attempt was made to lift a greater load at the free end of the boom than the vertical angle of the radius and boom would justify parts were strained and broken. It is also obvious that in other types of cranes, such for example as

2

traveling, hammer head, stiff leg, and jib cranes, the same problem is present.

It is the principal object of the present invention, therefore, to provide visual indicating means positioned conveniently in view of the operator and associated with pressure responsive means, whereby the radius of the boom is directly indicated, as well as the maximum weight to be lifted for a given radius, and indicating means then function to indicate the amount of weight or lifting force which is being imposed upon the boom, whereby a direct reading can be obtained to indicate the amount of load being lifted and to indicate when the magnitude of the load exceeds the maximum for the set radius of the boom.

The invention contemplates the provision of indicating means associated with the boom of a crane, whereby a dial will be moved to indicate the maximum load to be lifted by the boom at a set radius, said structure also including weight responsive means acting to move an indicating hand with relation to a dial to designate the amount of strain being placed on the hoisting cables or the amount of load being lifted.

The invention is illustrated as showing a boom type crane, by way of example, in the accompanying drawings, in which:

Figure 1 is a view in perspective showing a boom crane with the indicating mechanism applied thereto.

Fig. 2 is a view in diagram showing the position of the various elements of the invention and the manner in which the boom radius is calculated.

Fig. 3 is a view showing the dial of the indicating element when set for a particular radius.

Fig. 4 is a view showing the dial of the indicating device with the indicating hand moved in conjunction with the dial face.

Fig. 5 is a view showing the indicator with the cover plate removed to disclose the operating mechanism and the Bourdon tubes.

Fig. 6 is an enlarged view in section and elevation on the line 6—6 of Fig. 5 showing the dial and indicator hand operating mechanism with parts broken away for the sake of clearness.

Fig. 7 is an enlarged fragmentary view showing the manner in which the tackle and main hoisting block are mounted at the end of the boom.

Fig. 8 is an enlarged view in section showing the angle indicator reservoir.

Referring more particularly to the drawings, 10 indicates a platform or tower upon which a turntable 11 is mounted. A control cab 12 is carried upon the turntable and is associated with

a power unit 13. Extending upwardly above the structure and rotatable with the turntable is a mast 14. Mounted upon the turntable is a boom 15. The boom 15 is suitably pivoted for vertical movement upon a heel pin 16. A boom rigging is provided including cables 17, one of which is attached to the free end of the boom, as indicated at 18. A block 19 may form a part of the boom rigging so that a cable 20 may pass around a sheave 21 carried at the upper end of the mast and may be led downwardly, as indicated at 22, to the power unit, which includes a winding drum not shown in the drawings.

Mounted upon the boom 15 and adjacent to its free end is a sheave 23 over which a hoisting cable 24 is led to a suitable winding drum forming a part of the power unit generally indicated at 13. The hoisting cable 24 is led around a pair of sheave blocks 25 and 26 which are suspended from the free end of the boom. The sheave block 26, which is part of the main block, carries a hook 27 or a sling by which an object to be lifted may be engaged. Interposed between the main sheave block 26 and the secondary sheave block 25 is a fluid responsive unit 28. This unit is of the general type covered by Patent No. 1,771,340 issued to Walter R. Martin, one of the joint applicants herein, on July 22, 1930. This generally includes a hollow receptacle 29 here shown as secured to the sheave block 25 by a cable 30. A diaphragm 31 closes the open side of this receptacle and is flexible. A pressure plate 32 bears against the diaphragm and is fitted with a post 33 which engages a cable length 24'. Fluid is disposed within the cavity formed by the housing of the receptacle 29 and the diaphragm 31 so that as tension is applied to the hoisting cable 24 the diaphragm will flex in proportion to the force exerted. A tubular conduit 34 connects with the chamber in the structure and leads to an indicating device generally indicated at 35 in Fig. 5 of the drawings. Thus, as tension increases upon the cable 24 in an effort to lift the load which may be imposed upon the hook 27 the magnitude of the force imposed will be transmitted to the indicator 35 and there visually indicated.

The fluid responsive structure 28 is shown located between the sheaves 25 and 26 and as illustrated in Fig. 7 of the drawings it is placed upon the dead end 24' of the hoisting cable. The post 33 will engage the cable at a point intermediate hooks 36 and 37, so that as the force tends to straighten the dead-end length of cable 24' force will be imparted to the diaphragm 31 to expel the incompressible fluid within the structure and to force it through the conduit 34 to the indicator 35.

Referring more particularly to Figs. 5 and 6 of the drawings, it will be seen that the indicator 35 is provided with a circular housing 38 within which concentric Bourdon tubes 39 and 40 are positioned. The tube 39 is outermost and is spaced from the tube 40. These tubes are connected with a manifold block 41 through which are passageways for fluid entering the tubes. An extension tube 42 is connected with the manifold block 41 and communicates with the Bourdon tube 39. For convenience, the Bourdon tube 39 will be designated as the boom tube, and the Bourdon tube 40 will be designated as the weight tube. The extension tube 42 leads to a connection 42' carried on the housing 38 and to which a conduit 45 is attached for a purpose to be herein-after described. An extension tube 43 connects

with the manifold block 41 and establishes communication with the weight tube 40. A connecting structure 44 is carried by the case 38 and provides an attachment for the extension tube 43. The conduit 45 is attached to the connection 44 and leads to the weight indicator structure generally indicated at 28 in the drawings.

The boom Bourdon tube 39 is fitted at its free end with an adjusting link 46 which is attached to a gear segment 47 through an adjustable extension 47'. The gear segment 47 is mounted on a pivot pin 48 in a bearing frame structure shown in detail in Fig. 6 of the drawings. The gear segment 47 is in mesh with a pinion 48' carried upon a sleeve 49 rotatably supported in the bearing structure. The free end of the weight Bourdon tube 40 is provided with an adjustable and resilient link structure 50 which is attached to a gear segment 51 through an adjustable extension 51'. The adjustable link 50 is formed with a resilient U-shaped portion 52, the effective length of which may be changed by a sliding block 53, for a purpose to be hereinafter set forth. The gear segment 51 is mounted upon a pivot pin 54 which is carried by the bearing structure. The teeth of the gear segment 51 are in mesh with a pinion 55 fixed upon a pin 56 which extends upwardly through the bearing structure and the sleeve 49. The bearing structure is formed with a post 57 which carries a pair of coil springs 58 which are secured to the sleeve 49 and act in opposition to the distension of the boom tube 39. This post also carries a coil spring 59 secured to the pin 56. This operates in opposition to the action of the weight tube 40 to restore the shaft 56 to its original position. It is to be understood that stops are provided to limit the swinging movement of the gears 47 and 51, although they are not shown in the drawings. In order to protect the springs 58 so that they will not become entangled with the gears, shield discs 60 are mounted upon the sleeve 49. The sleeve 49 carries a central fitting 61 upon which a boom angle indicating disc 62 is secured. This moves with relation to a fixed dial ring 63. Fixed upon the upper end of the shaft 56 is a weight indicating hand 64. This moves over the face of the boom angle disc 62 and also with relation to the graduations on the fixed indicating ring 63.

The indicator disc 62 is moved automatically with reference to the vertical angular relation of the boom 15. This is brought about by a reservoir 65, which is in the shape of a cylindrical container or bucket having a cover 66 formed with a central opening 67. The opening 67 communicates with the atmosphere, and within the bucket a liquid is placed, preferably of a non-evaporating character. A bail 68 is connected to the reservoir and is pivotally mounted upon a member 68' carried at the free end of the boom. Thus, at all times the reservoir is swinging free to assume a vertically aligned position irrespective of the vertically inclined position of the boom 15. Connected with the lower end of the reservoir is the tubular conduit 45, which leads to the connection 42' through which communication is established with the Bourdon tube 39. It will be seen that as the angular position of the boom 15 changes the reservoir 65 will be raised or lowered, as the case may be, and the hydrostatic head of the liquid within the reservoir and the conduit 45 will be changed directly in proportion to the angle of the boom. Thus, varying hydrostatic pressure will be created through the Bourdon tube 39 to rotate the disc 62.

When the disc 62 is in position with the boom 15 extending horizontally, a pointer 70 on the disc 62 will be in alignment with a graduation 71 on the fixed dial 63. The dial 63 is formed with two sets of graduations disposed concentrically. The inner graduation extends along a band 72 and indicates the radius in feet of the boom 15. It has previously been explained that the radius in feet represents the distance from the center of the crane turntable to the point of support of the main hoisting block 26 as measured in a horizontal plane. An outer band of graduations 73 is mounted upon the fixed dial 63 and represents the capacity of the boom in tons for a particular radius. The movable disc 62 is formed with graduations 74 over which the hand 64 swings. These graduations represent the amount of lifting force being applied to the boom cable, and it will be evident that when the pointer 70 on the disc 62 moves to register with a graduation along the band 73 the maximum safe load capacity of the boom at a set radius will be indicated, and that thereafter the movement of the hand 64 over the disc 62 will apprise the operator of the actual load being lifted.

From the foregoing description it will be recognized that while the boom is being adjusted to a desired angle that the boom angle disc 62 and the indicating hand must move in unison with the point of the indicating hand in register with the pointer 70 on the disc 62. This feature of the invention is basically important, since the pointer 70 must designate the angular position of the boom with reference to the graduations 72 on the fixed indicating ring 63 and with reference to the graduations 73 on the indicating ring 63, which reading will indicate the safe load to be raised at a desired radius. In order to bring this action about the conduit 34 which leads from the weight indicator 28 to the indicator structure 35 is filled with liquid and will produce a hydrostatic head in the conduit 34 depending upon the angular position of the boom. This variation in hydrostatic head will act through the weight Bourdon tube 40 to move the lever extension 51 and the gear segment 51. It is to be understood also that the conduit 45 is filled with liquid, and that a hydrostatic head will thus be established in the conduits 34 and 45. This hydrostatic head will change in value in both conduits simultaneously as the boom is raised and lowered. It is necessary to insure that this simultaneous change will act through the Bourdon tubes 39 and 40 to move the boom angle disc 62 and the indicating hand 64 simultaneously and in unison. In order to do this the connecting link 46 is secured to the free end of the Bourdon tube 39 and is attached to the extension 47' of the gear segment 51. The connecting link 50 is attached to the free end of the tube 40 and is also attached to the extension 51' of the gear segment 51. These links are so adjusted as to insure that the sleeve 49 and the shaft 56 shall rotate in unison when the boom angle changes. To obtain accurate adjustment the adjusting block 53 may be moved back and forth on the U-shaped spring 52 of the link structure 50. This will determine the length of the link structure 50 to a nicety.

In operation of the present invention the structure is assembled as here shown, and the conduits 34 and 45 are led from approximately the same position at the end of the boom to the indicator device 35 to which they are attached at 44 and 42', respectively. At this time the boom is standing in its extreme horizontal position

and the hook 27 is supported from the cable 24 without any weight on it. The zero (0) point of scale 74 and the pointer 70 on dial 62 and the pointer 64 then coincide with the graduation 71 on fixed indicating ring 63. The boom is then manipulated to obtain a desired radius. As it does this its outer end will be elevated and will increase the hydrostatic head of liquid in conduits 34 and 45 simultaneously. This results in simultaneous movement of the boom angle disc 62 and the indicating hand 64 with relation to the fixed indicating ring 63. The boom angle disc 62 will move with relation to the fixed indicator ring 63 so that the zero point on the line of calibrations 74 and the pointers 64 and 70 will move to register with the calibrations on the fixed indicator ring. This will indicate the radius produced by the angularity of the boom and also the safe load to be lifted by the boom when disposed at that particular radius. For example, in Fig. 3 of the drawings the pointer 70 on the disc 62 is in register with approximately the point 12.5 on the calibrations 73 of the indicator ring and the point 78 of the calibrations 72. Simultaneously with this registration the indicator hand 64 moves to the same point. The registration thus indicates that the boom radius is 78 feet and that a safe load is 12.5 tons. In view of the fact that the boom angle will not change while lifting the load the boom angle disc will now remain stationary, and as the load is imposed on the hook 27 the indicating hand 64 will swing over the face of the disc 62, and as it swings over the graduations 74 the weight imposed upon the hook will be indicated by the hand 64 as shown in Fig. 4. When the hand 64 reaches the calibration 12.5 on the disc 62 the operator will then be apprised of the fact that he has imposed all of the load upon the hook which would be a safe load. The only way that he could safely lift a heavier load would be to shorten the boom radius, and when that is done the disc 62 will rotate to bring the pointer 70 into register with other calibrations on the fixed indicating ring agreeing with the angular disposition of the boom. At this same time the change in hydrostatic head in the conduit 34 would move the indicating hand 64 in unison therewith.

Figure 2 is a view in diagram illustrating the manner in which angles of force change when the boom is disposed at different angles to the horizontal. The dimension D is the actual radius of the boom as measured from the vertical axis of the boom to a line perpendicular to the end of the boom. The dimension D is the important distance to consider, since that will determine the overhang of the boom load from the center of the crane. The dimension A represents the actual length of the boom from the pin 16. The dimension E represents the distance between the central axis of the boom to the vertical axis intersecting the pin 16. The dimension C represents the height of the end of the boom with relation to the cab floor, and in this case would be the altitude of a triangle forming a part of the calculations automatically made by the present instrument. The factors B and F are angles of inclination of the boom relative to the horizontal plane intersecting the axis of the boom pivot 16, and the dimension G represents the height of the gauge above the horizontal plane of the axis of the pivot 16. All of these dimensions and angles normally figure in a calculation to determine the safe load to be lifted by the boom at any radius length D. The

present device makes all of these calculations automatically and instantly and gives a direct reading on the dial of the instrument, as shown in Fig. 3.

It will thus be seen that the apparatus here provided and associated with a crane boom automatically acts to give the operator a direct reading of the boom radius at all times and a direct reading of the safe load which could be carried at that radius, and that furthermore, the amount of weight imposed upon the boom can be read at all times, all of said readings being presented in the face of one instrument, where the readings may be simultaneously observed.

While we have shown the preferred form of our invention as now known to us, it will be understood that various changes may be made in combination, construction and arrangement of parts by those skilled in the art, without departing from the spirit of the invention as claimed.

Having thus described our invention, what we claim and desire to secure by Letters Patent is:

1. In combination with a crane including a boom having a hoisting block at the free end thereof and means by which the radius of the boom may be set adjustably, load responsive means associated with the hoisting block, an indicating structure including a fixed dial having thereon graduations indicating boom radii, a movable dial carrying graduations indicating the load imposed upon the boom and having a pointer moving with relation to the graduations on the fixed dial, a hand adapted to move over the face of the movable dial, hydrostatic means connected with the movable dial and acting in direct response to the set radius of the boom to rotate the dial with reference to the fixed dial and thus indicate the radius at which the boom is set, separate hydrostatic means connected with said load responsive means and said indicating hand, the movable dial and indicating hand moving in unison as the angle of the boom changes, said separate hydrostatic means being responsive to the load imposed upon the free end of the boom and said load responsive means for moving the indicating hand over the movable dial when the angle of the boom has been fixed and thereby indicating the magnitude of the load with relation to the movable dial.

2. In combination with a boom crane, radius and load indicating means, comprising a fixed circular dial having graduations therearound indicating boom radius and maximum safe load at a given boom radius, a movable circular dial carrying a pointer adapted to register with the graduations of the fixed dial as it moves, a hand mounted upon a pivot concentrically of said dials and passing over the faces thereof, fluid responsive weight indicating means connected with means for operating said hand to indicate the amount of lifting force being applied at the free end of the boom and for moving the indicating hand as the boom angle changes, and hydrostatic means associated with the boom and the movable dial, whereby the movable dial will rotate to dispose its pointer at a calibration on the fixed dial to indicate the radius of the boom and the maximum safe load which may be lifted by the boom at a particular radius.

3. An indicator of the character described adapted to operate in conjunction with a boom, comprising a case, a weight indicating Bourdon tube within the case, a radius indicating Bourdon tube within the case, a center pin, a sleeve rotat-

able with relation thereto, operating means between the first named Bourdon tube and the pin for rotating the same under flexure of the tube, operating means connected with the second named tube and rotating the sleeve, a fixed annular dial having graduations thereon indicating radii of the boom and maximum safe loads for the boom at given radii, a rotatable dial disc mounted upon the sleeve and having a pointer to register with graduations on the fixed dial, said dial disc also carrying graduations indicating load weights, an indicating hand carried upon the pin and swinging over the faces of the dials and their calibrations, fluid pressure responsive means connected with means adjacent the free end of the boom and also connected with the first mentioned Bourdon tube, whereby the weight imposed upon the free end of the boom will act to move the indicating hand appropriately, and hydrostatic means mounted at the free end of the boom and associated with the second named Bourdon tube to rotate the dial disc with relation to the fixed dial.

4. An indicator of the character described adapted to operate in conjunction with a boom, comprising a case, a weight indicating Bourdon tube within the case, a radius indicating Bourdon tube within the case, a center pin, a sleeve rotatable with relation thereto, operating means between the first named Bourdon tube and the pin for rotating the same under flexure of the tube, operating means connected with the second named tube and rotating the sleeve, a fixed annular dial having graduations thereon indicating radii of the boom and maximum safe loads for the boom at given radii, a rotatable dial disc mounted upon the sleeve and having a pointer to register with graduations on the fixed dial, said dial disc also carrying graduations indicating load weights, an indicating hand carried upon the pin and swinging over the faces of the dials and their calibrations, fluid pressure responsive means including a closed receptacle having a yieldable wall, said receptacle containing an incompressible fluid, the wall being acted against by the load suspended at the end of the boom, a tubular conduit connecting said receptacle with the first named Bourdon tube, a tubular conduit connected with the second named Bourdon tube, and a liquid reservoir carried at the free end of the boom and connected with said last named conduit, whereby variation in elevation of the free end of the boom will cause proportionate variation in the hydrostatic head of the liquid in the reservoir and its conduit.

5. In combination with a crane including a boom having a hoisting block at the free end thereof and means by which the radius of the boom may be set adjustably, an indicating structure including a fixed dial having thereon graduations indicating boom radii and the maximum safe load for any given radius, a movable dial carrying graduations indicating the load imposed upon the boom and having a pointer moving with relation to the graduations on the fixed dial, a hand adapted to move over the face of the movable dial, means connected with the movable dial and acting in direct response to the set radius of the boom to rotate the dial with reference to the fixed dial and thus indicate the radius at which the boom is set and the maximum safe load to be lifted by the boom at said radius, means causing said hand to move in unison with the movable dial as said boom angle changes and to respond to the load imposed upon the free end of the boom

for moving the indicating hand over the movable dial and thereby indicating the magnitude of the load.

6. In combination with a boom-type crane carrying a hoisting block at its free end and having means by which the radius of the boom may be adjusted and the hoisting block raised, an indicating structure including a liquid filled conduit extending substantially from the base of the boom to its outer free end and whereby as the radius of the boom is shortened the hydrostatic head of liquid in the conduit will be increased, a fluid responsive weight indicating structure connected with the hoisting block to indicate the amount of weight imposed thereon, a conduit leading from 15 said fluid responsive weight indicating structure to a point near the free end of the boom and then leading downwardly to the base of the boom, said conduit and fluid responsive means being filled with liquid whereby when the angle of the boom is shortened the hydrostatic head of liquid in this conduit will increase, an indicator disposed adjacent the base of the boom and within which a fluid responsive means is connected with the first named conduit and a separate fluid responsive means connected with the second named conduit, a fixed indicator ring carrying graduations designating different lengths of boom radius and corresponding different safe loads, an indicator chart carrying an index point to move with reference to the graduations on the fixed indicator ring and carrying graduations indicating different weights, said chart being moved by the fluid responsive means connected with the first named liquid con-

duit, an indicating hand adapted to move over the face of said indicator chart as actuated by the second named fluid responsive means, a connection between the indicator chart and its fluid responsive means, and a yieldable connection between the hand and its fluid responsive means whereby a change in boom radius and a resultant change in the hydrostatic head of the liquids in the two conduits will cause the said indicator chart and indicating hand to move in unison and when weight is imposed upon the hoisting block to cause the indicating hand to move with relation to the said indicator chart.
